UNITED STATES PATENT OFFICE

ANGELO PITTONI, OF LYNBROOK, NEW YORK, ASSIGNOR TO THE ROME COMPANY, INC.,
OF ROME, NEW YORK, A CORPORATION OF NEW YORK

FOLDING BED

Application filed August 22, 1928. Serial No. 301,185.

The present invention relates to folding couch or day beds of the general type consisting of a main stationary frame section and a movable or extension bed section and 5 in which the extension bed section is movable either into superposed relation with the stationary section to form a couch or seat or laterally of the stationary section to form a double bed. More particularly my invention relates to beds of this type in which 10 the stationary and extension bed sections are each provided with a mattress supporting spring structure having helical springs of a depth normally used in stationary beds 15 of this size and in which the spring structure of the stationary section is on an inner movable bed section, which is elevated or lowered simultaneously with the moving of the extension section to its open or closed positions respectively.

The general object of my invention is to provide an improved construction and arrangement of the various parts of a couch bed of the type described. A more specific 25 object of my invention is to provide simple and effective means for assisting the user in simultaneously moving the spring structures of the stationary and extension sections to either the open or closed positions. A further object of my invention is the provision 30 of a storage space for the mattress and bedding between the deep helical spring structures of the sections when the sections are in the closed position.

The various features of novelty which characterize my invention are pointed out with particularity in the claims annexed to and forming a part of this specification. For a better understanding of the invention, 40 however, and the advantages possessed by it reference should be had to the accompanying drawings and descriptive matter in which I have illustrated and described a preferred embodiment of the invention.

Of the drawings:

Fig. 1 is an end elevation with one of the end frames removed and other parts broken away of the bed in the closed position;

Fig. 2 is a side elevation with parts broken away;

Fig. 3 is a section on the line 3—3 of Fig. 1;

Fig. 4 is an end elevation of the bed in 55 the open position; and

Fig. 5 is a plan view of the bed in the open position.

In the drawings I have illustrated a preferred embodiment of my invention in which 60 the stationary main frame bed section comprises a U-shaped tubular frame member A at each end of the bed. A similarly shaped end frame member B of the same width but of less height is secured to end member A. 65 Each end frame B is made of an angle bar bent to provide vertical legs B' and B² and a horizontal portion B³. A horizontal cross bar B⁴ connects the lower portions of the legs B' and B². Side floor bars B⁶ extend 70 longitudinally between the frame members B. Reinforcing corner pieces B⁵ connect the horizontal portion B³ to each of the legs. A second horizontal cross bar C formed of angle iron has its ends connected to the legs 75 B' and B² at points intermediate the bars B³ and B⁴. The angle bar C is arranged with its horizontal leg C' extending outwardly between the legs B' and B² and its vertical leg C² provided with a pair of narrow longitudinally extending slots C³ and C⁴ horizontally spaced apart.

The main stationary frame section is provided with an inner movable bed section consisting of a spring structure D having 85 a rectangular spring frame D' of angle iron, a series of helical spring coils D² suitably connected at their upper and lower ends, and a border rod D³ supported by and connected to the marginal spring coils. The 90 lower ends of the marginal spring coils are connected to the frame D'.

The extension bed section which is also positioned between the frame members A is also provided with a spring structure E 95 similar to the spring structure D of the main section and comprising a rectangular frame E', helical coils E² and border rod E³. Vertical legs E⁴ are secured to the two outer corners of the frame E' and are slightly 100

longer than the legs B' and B^2 of the stationary frame. Each end member of the frame E' is provided at its outer side with a flat bar E^5 bent into the form of a flat-tened U and having end flanges E^6 riveted to the frame.

In the normal closed position of the bed the spring structure D is positioned below and vertically spaced from the extension spring structure E with the extension spring alone serving as a resilient support for the occupant. The space between the springs can be utilized as a storage space for the main spring mattress and other bedding.

The spring structures D and E are pivotally connected to the end frames B and to each other in such a manner that when the extension spring E is moved to the open position, the main spring structure will be simultaneously elevated to substantially the same position occupied by the extension spring in the closed position of the bed. The pivoted connections at each end comprise a pair of parallel levers or links F and G , the upper end of the link F being inwardly offset and pivotally connected to the adjacent end bar of the frame E' at one end thereof and the upper end of the link G also being inwardly offset and pivotally connected to the end bar at a point horizontally spaced from the pivot connection of the link F . The pivoted end of the link G is enclosed by the U -shaped bar E^5 .

The link F is provided with a projecting stud F^2 at a point adjacent its lower end and positioned in the slot C^3 in the vertical leg of the cross-bar C . The link G is similarly provided with a stud G^2 positioned in the slot C^4 . A rigid distance link H connects the studs F^2 and G^2 together on the outer side of the cross-bar vertical leg. The links F and G are provided with rigid lateral extensions F^3 and G^3 , respectively, projecting downwardly at an angle from points on the links immediately above the studs F^2 and G^2 respectively. Braces F^4 and G^4 , respectively, reinforce the connections between the extensions F^3 and G^3 and their respective links. The lower ends of the extensions are inwardly offset and pivotally connected to the adjacent end bar of the spring frame D' at horizontally spaced points by pivot pins F^5 and G^5 , respectively. A distance link K is pivotally connected to one end of the cross-bar C adjacent the leg B' and has its opposite end pivotally connected to the extension F^3 at a point K^2 on the extension above the pivotal connection of the extension with the frame D' .

The brace G^4 as shown in Fig. 1 projects beyond the link G and is positively connected to the corresponding brace at the opposite end of the bed by an angle bar M . A short link N is pivotally connected to the lower end of the link F which projects

downwardly beyond the stud F^2 . A tension spring O is connected between the lower end of the link N and the frame leg B^2 at a point immediate below the cross bar C . A second tension spring P is connected between the link F at a point above the stud F^2 and the leg B^2 at a point above the cross bar C .

The parts have been described particularly with reference to Figs. 1-3 where the bed sections are shown in the closed position. When it is desired to move the sections to the open position, the side bar of the extension frame E' is grasped by the user and the extension section lifted upwardly and outwardly. This movement is initially assisted by the spring P which is in its extended position when the sections are in the closed position. Simultaneous with the movement of the extension section the spring structure D is moved upwardly in a substantially perpendicular path due to the connection of the distance link K with the extension F^3 of the link F . The pivot points F^2 and G^2 move slowly to the right while the link K is moving from the position shown in Fig. 1 to a substantially horizontal position. On a further upward movement of the links, the pivot pins move to the left until the extension section is in the open position. At that point the pivot pins are at the extreme left end of the slots C^3 and C^4 . The movement of the links F and G from a substantially vertical position to the open position of the sections shown in Fig. 4 is accompanied by a tensioning of the spring O , which thus prevents a too rapid downward movement of the extension section.

The extension section is supported in the open position by the legs E^4 and by the upper portion of the link G contacting with the bent portion of the U -shaped bar E^5 . As shown in Fig. 4 the springs of both sections are at the same level when the bed is in the open position and the adjacent sides of the springs are slightly spaced apart. There is no tendency for the inner bed section to drop and the extension section to rise due to a heavy load on the spring D as such loads are transmitted downwardly to the supporting links at points on the side of the link pivots tending to hold the sections in the open position. While it is preferable that the user grasp the middle portion of the frame side when operating the bed, the movements can be effected at any point along the frame side. The bar M effects a positive connection between the operating mechanism at each end of the bed.

When it is desired to restore the bed to the closed position, the extension section is lifted and moved inwardly. The spring action in this case is the reverse of that occurring during the opening movement and the spring O first assists in the return movement and the

spring P later retards the lowering of the extension section into position. The extension spring is supported in the closed position partly by the link G contacting with the other bent portion of the U-shaped bar E⁵, partly by the legs E⁴ and partly by the bar M which contacts with the lower side of the frame E'.

My invention is characterized by the simplicity, strength and ease of manipulation of the construction, by the facilities for storing the bedding with spring structures of this type, by the small amount of floor space required in both the open and closed positions of the bed, and the maintenance of the supporting spring structure at the same high level in both the open and closed positions.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. A couch bed comprising a main stationary frame, an inner movable bed section, a movable extension bed section normally positioned above said inner bed section and movable relatively thereto to a position at one side thereof, a spring mattress structure for each of said bed sections, and mechanism for guiding the movements of said bed sections in an upright condition, said mechanism comprising a pair of levers at each end of said bed, each of said levers having a fixed pivot connection with each of said spring structures and a movable pivot connection with said stationary frame.

2. A couch bed comprising a main stationary frame, an inner movable bed section, a movable extension bed section normally positioned above said inner bed section and movable relatively thereto to a position at one side thereof, a spring mattress structure for each of said bed sections, and mechanism for guiding the movements of said bed sections in an upright condition, said mechanism comprising a pair of levers at each end of said bed, each of said levers having a fixed pivot connection with each of said spring structures and a movable pivot connection with said stationary frame, a bar extending longitudinally of the bed and connected to corresponding levers of each pair, said bar being arranged to partially support the extension bed section in the closed position.

3. A couch bed comprising a main stationary frame, an inner movable bed section, a movable extension bed section normally positioned above said inner bed section and movable relatively thereto to a position at one side thereof, a spring mattress structure for each of said bed sections, and mechanism at each end of the bed for guiding the movements of said bed sections, in an upright condition to open and closed positions of said bed, said mechanism comprising a pair of levers having stationary pivot connections with said bed sections and movable pivot connections with said stationary frame, and a distance link connecting one of said levers of each pair with said stationary frame, whereby said inner bed section is moved substantially vertically simultaneously with the movement of said extension bed section to said open position.

4. A couch bed comprising a main stationary frame, an inner movable bed section, a movable extension bed section normally positioned above said inner bed section and movable relatively thereto to a position at one side thereof, said movable bed sections having a rectangular frame and a spring mattress supported thereby, and mechanism for guiding the movements of said bed sections in an upright condition to open and closed positions, said mechanism comprising a pair of parallel levers at each end of said bed, each of said levers having fixed pivot connections with the end portions of each of said spring frames and a movable pivot connection with said main stationary frame, and means on said extension sections spring frame cooperating by engagement with one of said levers to support said extension section in said open and closed positions.

5. A couch bed comprising a main stationary frame, an inner movable bed section, a movable extension bed section normally positioned above said inner section and movable relatively thereto to a position at one side thereof, a spring mattress structure for each of said bed sections, and mechanism for guiding the movements of said bed sections in an upright condition to open and closed positions of said bed, said mechanism comprising a pair of parallel levers at each end of said bed, each of said levers having fixed pivot connections with each of said bed sections and a movable pivot connection with said stationary frame, and tension springs extending between said stationary frame and one of said levers of each pair at opposite sides of said movable pivot connection.

6. A couch bed comprising a main stationary frame, an inner movable bed section, a movable extension bed section normally positioned above said inner section and movable relatively thereto to a position at one side

thereof, a spring mattress structure for each of said bed sections, and a mechanism at each end of the bed for guiding the movements of said spring structures in an upright condition to open and closed positions of said bed, said mechanism comprising a pair of levers, each of said levers having a stationary pivot connection with said extension bed section and a movable pivot connection with said stationary frame, a rigid lateral extension on each of said levers having a stationary pivot connection with said inner section, a distance link connecting one of said lateral extensions with said stationary frame, whereby said inner section is moved substantially vertically simultaneously with the movement of said extension section to the open position of the bed.

Signed at Long Island City, in the county of Queens and State of New York, this 20th day of August, A. D. 1928.
